(57) **CLAIM**

The ornamental design for a bicycle frame, as shown and described.

DESCRIPTION

FIG. 1 is a top, rear, and right side perspective view of a bicycle frame showing my new design;

FIG. 2 is a front and left side perspective view thereof;

FIG. 3 is a front elevation view thereof;

FIG. 4 is a left side elevation view thereof, to which the right side elevation view is a mirror image; and,

FIG. 5 is a top plan view thereof.

The broken lines in the drawings illustrate portions of an environmental bicycle that form no part of the claimed design.
